(57) **CLAIM**

See application file for complete search history.

I claim the ornamental design for a reinforced-ring container for beverage making-products, as shown and described.

(56) **References Cited****DESCRIPTION**

U.S. PATENT DOCUMENTS

FIG. 1 is a bottom perspective view of a reinforced-ring container for beverage making-products of the present invention;

D288,063 S *	2/1987	Tyler	.....	D9/425
D383,646 S *	9/1997	Jeppesen et al.	.....	D7/545
6,431,389 B1 *	8/2002	Jerstroem et al.	.....	220/574.3
D502,362 S	3/2005	Lazaris et al.		
D606,363 S *	12/2009	Aardenburg	.....	D7/584
D606,404 S *	12/2009	Diss	.....	D9/500
D612,732 S *	3/2010	Takata et al.	.....	D9/500
D647,397 S *	10/2011	Inaba	.....	D9/428

FIG. 2 is a side elevation view thereof, with all other side views being the same; and,

FIG. 3 is a bottom plan view thereof.

The ornamental design which is claimed is shown in solid lines in the drawings. The top is not shown, as it forms no part of the claimed design.
